UNITED STATES PATENT OFFICE.

JOHN AUGUSTUS HICKS, OF SUMMIT, NEW JERSEY, ASSIGNOR TO JAMES M. HICKS, OF SUMMIT, NEW JERSEY.

MEANS FOR REMOVING SEALING-CAPS FROM VESSELS.

No. 835,789.

Specification of Letters Patent.

Patented Nov. 13, 1906.

Application filed February 3, 1906. Serial No. 299,244.

To all whom it may concern:

Be it known that I, JOHN AUGUSTUS HICKS, a citizen of the United States, residing at Summit, Union county, New Jersey, have invented certain new and useful Improvements in Means for Removing Sealing-Caps from Vessels, of which the following is a specification.

My invention relates to means for removing sealing-caps from vessels; and it consists in certain elements, in combination, fully set forth in the following specification and claimed at the end thereof.

In order that those skilled in the art to which my invention appertains may understand, construct, and use my invention, I will proceed to describe it, referring to the accompanying drawings, forming part thereof, in which—

Figure 1 is a front elevation and part longitudinal central section of my invention applied to a sealing-cap secured to a vessel over its mouth. Fig. 2 is a partial side elevation and part central longitudinal section of my invention on a vessel having a bead. Fig. 3 is a top view in part and part cross-section of Fig. 2 beneath the metal of the top surface and above the inclosed wafer and showing a part of the removing means F lying above the wafer D in the cap. Fig. 4 is a vertical longitudinal section of a cap and flange and a removing means F in side view, F in this figure being a narrow strip instead of a wire, as in Figs. 1, 2, and 3. Fig. 5 is a front elevation of Fig. 4 and shows a collar on the top of the vessel-neck straight-sided, not a bead, as in Figs. 1 and 2. Fig. 6 is a vessel in front elevation, showing no bead and no collar and having my invention applied to it. Fig. 7 shows in front elevation a milk-jar provided with my invention.

A is the vessel-neck. B is the usual bead at its top in Figs. 1 and 2 and a rim or collar in Figs. 4 and 5.

C is a sealing-cap secured over the vessel-mouth and having a wafer D in it, as is usual.

F is a wire in Figs. 1, 2, 6, and 7, secured in the cap C over the wafer D and extending downward below the flange of the cap, ending

in a loop E, by which it may be grasped to remove the cap. 50

In Figs. 4 and 5 F is a thin narrow strip of metal.

The cap provided with wafer and wire or metal strip F is secured over the vessel-mouth in the manner set out in Patent No. 783,038, dated February 21, 1905, the flange of the cap being smaller than the bead or collar upon the vessel-neck including the wire or strip F, over which the flange is stretched. 55 The removal of the cap is accomplished by drawing upward the loop E and lifting the cap off, or when F is a wire and the cap is made of thin pliable metal the wire F tears the cap-flange, thus releasing its hold upon 60 the vessel. This method of removing sealing-caps which are stretched over the vessel-neck is especially advantageous where the vessel has a collar or straight-sided band upon it, and a cap with a flange stretched 65 over this band cannot be removed readily without breaking the vessel-neck except by a longitudinal pull and that a very severe one. A cap removed in the ordinary way by lifting one side and turning the cap sidewise 70 pinches the straight sides of the collar and prevents the turning of the cap without unduly stretching the cap-flange and causes 75 great annoyance. By my invention caps are easily removed no matter what depth of 80 flange and shape of bead or collar it has and even when the vessel has no collar.

Having now fully described my invention and the manner in which I have embodied it, what I claim as new and as my invention, and 85 desire to secure by Letters Patent, is—

In a means for removing sealing-caps from vessels, the combination consisting of sealing-cap provided with a pendent flange which grips the vessel to secure it thereto, 90 compressible sealing means located beneath the top surface of said cap, a removing means partially inclosed within the sealing-cap and partially without the sealing-cap, the said removing means within the cap being impressed in the material of the sealing means, 95 between the under side of the top surface of the cap and the said sealing means and

2
closely compressed between the said flange of
the said cap and the bead upon the vessel-
neck, whereby when the cap is secured on a
vessel the said cap is removed therefrom by
5 drawing upon the end of the removing means
outside of the cap.

In testimony whereof I have signed my

name to this specification, in the presence of
two subscribing witnesses, this 2d day of Feb-
ruary, 1906.

JOHN AUGUSTUS HICKS.
